DESIGN.

G. G. WOLFE & A. LISEWSKI.

PARLOR STOVE.

No. 16,648.

Patented Apr. 20, 1886.

UNITED STATES PATENT OFFICE.

GURDON G. WOLFE AND AUGUST LISEWSKI, OF TROY, NEW YORK, ASSIGNEES TO THE FULLER & WARREN COMPANY, OF SAME PLACE.

DESIGN FOR A PARLOR-STOVE.

SPECIFICATION forming part of Design No. 16,648, dated April 20, 1886.

Application filed June 1, 1885. Serial No. 167,350. Term of patent 7 years.

To all whom it may concern:

Be it known that we, GURDON G. WOLFE and AUGUST LISEWSKI, both of the city of Troy, county of Rensselaer, State of New York, 5 have jointly invented and produced a new Design for Parlor-Stoves, and of which the following is a specification.

Our design relates to the form and ornamentation of the tops, the door-frames, and feet 10 of parlor-stoves as the same are shown in the accompanying photograph, forming a part of this specification.

The form of stove to which our design is shown as applied is that of a cylinder-stove 15 having a square base.

Our design for the top of the stove consists of a dome-form portion, P', which is smaller 20 in its transverse diameter than the stove-body B on which it is placed, and is somewhat flattened in its upward contour. Between this dome-form top and the stove-body there is an overhanging molded portion, P', having the downwardly and outwardly projected beveled molding p', extending from the dome-base d', 25 and the upwardly and outwardly beveled molding p', extended from the stove-body, with a beveled band-molding, p', arranged between the said opposite beveled moldings p' p', all the said moldings being produced in revolution upon the stove between the base of the dome-portion and the stove-body.

Our design for the door-frame F consists of the side pilasters, f', having outwardly-beveled and molded sides f", interior scale ornamentation, f", pendent grapes and leaf f", a lozenge ornament, f", and a pendent drop ornament, f", at the bottom of the pilasters.

The top of the door-frame is composed of the projecting overhanging molding f', which 40 at its longitudinal center is divided and separated for the intrusion of a leaf ornament, f", and at each side of the latter said overhanging molding f' curves in opposite directions downwardly and laterally, so as to subtend the 45 pilasters at each side of the frame, the said molding where over the pilasters being ornamented by a pedestal, f". The molding at the bottom of the door-frame is ornamented with two notched and filleted reversing curves, f", 50 and central scrolls, f".

Where in contact with the pilasters the bot-

tom of the door-frame is ornamented with two notched and filleted reversing curves, f".

The door that is shown within the frame F forms the subject of another application for a 55 design patent bearing even date herewith and made by us.

Our design for the lower door-frame (indicated at I) consists of the pilasters i', made with molded and beveled sides i", a quatrefoil 60 figure, i", in the front of the pilasters near their upper ends, the scale ornamentation i", the plinth i", the pyramidal-molded top, i", 65 surrounded by an immersed ball. Between the said side pilasters the top of the frame i' has two reversing fringed medallion scrolls, i", and between the latter is a pedestal, i", having at the front a radiate figure, i", and at the top of the cone-form ornament i". The bottom of said frame I consists of a filleted molding, i", 70 that joins the side pilasters.

The feet of the stove, as indicated at M, have a downwardly and outwardly slanting front with their sides so shaped to give them a V form, the feet on their front exterior surface being ornamented by a beaded line, m', across the top, the side edge fillets, m", the intermediately-placed fan ornaments, m", and relief leaf ornaments m' m".

Having thus described our design, what we 80 claim, and desire to secure by Letters Patent, is—

1. In a design for a stove, the ornamentation of the door-frame F, consisting of the side pilasters, f' f", the top molding, f', having a 85 central ornament, f", and pedestals f", and the reversely-scrolled bottom molding, f", as shown and described.

2. In a design for a stove, the ornamentation of the ash-pit door-frame I, consisting of the 90 pilasters i', the top molding, i', having a central ornament, i", and reversing scroll i" i", and the bottom molding, i", as shown and described.

3. In a design for a stove, the ornamentation 95 of the feet, consisting of their V form, the beaded line m' across their top, the fillets m" upon the sides, and the fan ornaments m" and the leaf ornaments m" on the exterior face of feet, as shown and described.

4. The design herein described and shown 100 for a parlor-stove, consisting of a cylindrical

body, the door-frame thereon having the side pilasters, $f' f'$, the top molding, f' , having a central ornament, f^a , and pedestals f^s , and bottom molding, f^{10} , and the door-frame I, having the pilasters i' , the top molding, i' , with central ornament, i^{10} , reversing scroll i' , and bottom molding, i^{11} , and the feet of the V form having beaded top line, m' , fillets m^s on the sides, and the fan and leaf ornaments $m^s m^s$.
5. The design herein described and shown for a parlor-stove, consisting of flattened dome-form top having the overhanging molding P' , the beveled moldings $p' p' p'$, a cylindrical body, the door-frame thereon having the side 10 pilasters, $f' f'$, the top molding, f' , having a central ornament, f^a , and pedestals f^s , and bot-

tom molding, f^{10} , the door-frame I, having the pilasters i' , the top molding, i' , with central ornaments, i^{10} , reversing scroll i' , and bottom molding, i^{11} , and the feet of V form having 20 beaded top line, m' , fillets m^s on the sides, and the fan and leaf ornaments $m^s m^s$.

Signed at Troy, New York, this 10th day of January, 1885, and in the presence of the two witnesses whose names were by them hereto 25 written.

GURDON G. WOLFE.
AUGUST LISEWSKI.
